UNITED STATES PATENT OFFICE.

FREDERICK H. CYRENIUS, OF OSWEGO, NEW YORK.

FOOT-BRUSH.

SPECIFICATION forming part of Letters Patent No. 414,145, dated October 29, 1889.

Application filed April 12, 1889. Serial No. 306,934. (No model.)

To all whom it may concern:

Be it known that I, FREDERICK H. CYRENIUS, of Oswego, in the county of Oswego, in the State of New York, have invented new and useful Improvements in Foot-Brushes, of which the following, taken in connection with the accompanying drawings, is a full, clear, and exact description.

This invention consists in a novel construction of a foot-brush which is simple, inexpensive, and yet strong, durable, and efficient in its operation.

The invention is fully illustrated in the annexed drawings, in which Figure 1 is a perspective view of my improved foot-brush. Fig. 2 is a vertical transverse section on line *x x*, Fig. 1; and Fig. 3 is a vertical longitudinal section on line *y y*, Fig. 1.

Similar letters of reference indicate corresponding parts.

A represents the base of the foot-brush, which base consists of a rectangular or elongated plate of wood or metal. To the end portions of said base are rigidly attached the cross-walls *c c*, which rest with their bases across the entire width of the base *A*, so as to effectually brace the same and prevent it from splitting when composed of wood. Between said cross-walls are arranged two longitudinal walls *b b*, one or both of which are formed separately from the base *A* and aforesaid cross-walls, and one of said longitudinal walls is rigidly secured to the cross-walls by screws or nails passing through the cross-walls and

into the ends of the longitudinal walls or by any other suitable and well-known means. The other longitudinal wall *b* is inserted removably between the cross-walls, and in the elongated space surrounded by the four walls is inserted vertically the broom *d*, which is clamped therein by ties *t t*, extending transversely through the two longitudinal walls. Said ties may consist either of bolts provided with nuts or wooden pins into the ends of which are driven wedges *e e*, as shown in Fig. 45 2 of the drawings.

Having described my invention, what I claim as new, and desire to secure by Letters Patent, is—

As an improved article of manufacture, a foot-brush composed of the elongated base *A*, cross-walls *c c*, resting with their bases across the entire width of the base *A* and rigidly attached thereto to brace the same, two longitudinal walls *b b*, one of which is rigidly secured to the cross-walls and the other is inserted removably between the cross-walls, the broom inserted vertically in the space surrounded by the aforesaid walls, and ties *t t*, extending transversely through the longitudinal walls, substantially as described and shown.

In testimony whereof I have hereunto signed my name this 8th day of April, 1889.

FREDERICK H. CYRENIUS. [L. S.]
